Frankland J. Amus.

UNITED STATES PATENT OFFICE.

JAMES W. BIRKETT, OF BROOKLYN, NEW YORK.

WATER-CLOSET ATTACHMENT.

SPECIFICATION forming part of Letters Patent No. 299,333, dated May 27, 1884.

Application filed January 14, 1884. (No model.)

To all whom it may concern:

Be it known that I, JAMES W. BIRKETT, a citizen of the United States, residing at Brooklyn, in the county of Kings and State of New York, have invented certain new and useful Improvements in Water-Closet Attachments; and I do declare the following to be a full, clear, and exact description of the invention, such as will enable others skilled in the art to 10 which it appertains to make and use the same; reference being had to the accompanying drawings, and to the letters and figures of reference marked thereon, which form a part of this specification.

15 My invention relates to certain improvements in water-closet attachments, the details whereof are fully described in the following specification, and clearly shown in the accompanying drawings, in which—

20 Figure 1 is a vertical longitudinal sectional view of my invention, and Fig. 2 is a similar view of a modification.

Like letters of reference indicate similar parts.

25 A refers to the bowl. B is the trap, and C the discharge-pipe. D indicates the pull-handle, E the exit-valve, and F the overflow for the bowl.

T is the trunk, within which I place the 30 mechanism for simultaneously operating the exit-valve E and liberating the water-supply; and this mechanism consists of the toggle-lever arms G G', connecting the exit-valve E and the bent lever H, and pivoted at their 35 inner ends to the vertical-moving pull-handle rod. At this point I insert the connecting link or ring R, for convenience and simplicity of mechanism, and to the upper side thereof the pull-handle rod is pivoted, while the toggle-lever arms are pivoted at or nearly at points 40 equidistant from the handle-rod. A less cumbersome joint is thus made, and the toggle-lever arms do not interfere with each other when the pull-handle is raised. At the same time their 45 operation is effective and simple, and the exit-valve E will be tightly wedged, when closed, between the packing and the lower end of the bent lever H. The bent lever H, when the pull-handle is raised, operates to communicate 50 horizontal movement to a push-rod, J, by

means of pin h and slot j. To the other end of this rod J, I connect the water-supply valve by means of a cord, K, fastened at any desired point, so that it will fall over the line of movement of said push-rod. The pulley L 55 is inserted in the end of rod J, and its grooved face runs on the cord. When the pull-handle is raised, the pulley L pushes cord K out of line, and thus shortens the direct distance between its ends. Power is thus communicated to the water-supply device. It is, however, evident that while this form of connection is described, any suitable or well-known mechanism may be employed that is capable of performing substantially the same function; 60 or the push-rod might be connected direct with the valve, as in Fig. 2, the system of levers remaining the same. The exit-valve E being suitably hung at e, when the pull-handle is raised, one arm of the toggle-lever opens 65 said exit-valve, and the other arm operates the water-supply through bent lever H, which is pivoted at i.

Through the exit-valve E, and at right angles thereto, extends the tube F, forming the 70 overflow for the bowl. The outer end of this tube is bent and continued upward to a height on a level with the desired water-level of the bowl. At every operation of said valve this overflow-tube is entirely emptied, thus avoiding clogging or stoppage, and facilitating the 75 successful working of the closet.

The fulcrum of the supporting-lever H and the hinge of the valve E being on opposite sides of the trunk, and the lower portion of said 80 lever H and the valve E both moving toward the center of the trunk, the intervening levers and connections between them will move simultaneously, and the power used to elevate or depress said pull-rod will be applied with- 85 out the intervention of any sliding parts.

I claim—

1. In a water-closet, a toggle-lever having vertically - moving connecting-link, and the outer ends of its arms pivoted to and supported, 90 respectively, by the exit-valve and the water-supply-operating lever, as set forth.

2. In a water - closet, the pull-handle D, push-rod J, pivoted bent lever H, and suitable connecting mechanism, in combination 95

with a valve-controlling cord fixed at one end and adapted to be drawn downward by the thrust of said push-rod, substantially as described.

5. 3. In a water-closet, the combination of exit-valve E, provided with suitable overflow, the toggle-levers G G', and connecting-link R, interposed between said toggle-levers and the pivoted bent lever H, said lever H also

being connected to and operating the water-supply-controlling devices, substantially as shown and described.

In testimony whereof I affix my signature in presence of two witnesses.

JAMES W. BIRKETT.
